(57) **CLAIM**

The ornamental design for a charger module, as shown and described.

DESCRIPTION

FIG. 1 illustrates a perspective view of a charger module. FIG. 2 illustrates a front view of a charger module. FIG. 3 illustrates a back view of a charger module. FIG. 4 illustrates a side view of a charger module. FIG. 5 illustrates a side view of a charger module. FIG. 6 illustrates a top view of a charger module; and, FIG. 7 illustrates a bottom view of a charger module. The broken lines shown are for the purpose of illustrating unclaimed portions of the charger module and form no part of the claimed design.
